UNITED STATES PATENT OFFICE.

ELIAS W. CONKELL, OF CANTON, OHIO, ASSIGNOR OF ONE-FOURTH TO JACOB J. HEIN
AND ONE-FOURTH TO WILLIAM A. HAMMERLY, BOTH OF CANTON, OHIO.

STEAM-ENGINE.

1,015,993.

Specification of Letters Patent.

Patented Jan. 30, 1912.

Application filed February 8, 1911. Serial No. 607,254.

To all whom it may concern:

Be it known that I, ELIAS W. CONKELL, a citizen of the United States, residing at Canton, in the county of Stark and State of 5 Ohio, have invented a new and useful Steam-Engine, of which the following is a specification.

My invention relates to improvements in steam engines adapted for the operation of 10 pumps and the like, although my invention may be embodied in steam engines for other purposes.

More specifically the invention refers to steam engines in which a balanced, steam 15 actuated valve is employed for the control of the ports of the cylinder.

The objects of my invention are to generally improve steam engines of the character mentioned, to provide a steam engine of few 20 and simple parts in which the amount of energy required to actuate the valves is reduced to a minimum, a main, steam balanced cylinder port controlling valve being controlled in its movements by an auxiliary valve 25 directly mechanically actuated by the piston in its movements.

A further important object of the invention is to provide a steam engine of the simplex type readily adapted to be used with a 30 second similar engine, the two engines being connected in such way as to produce a duplex steam engine of improved design.

These objects together with other objects which will be readily apparent to those 35 skilled in the art I attain by the construction illustrated in the accompanying drawings, although my invention may be embodied in other forms, the construction illustrated being chosen by way of example.

40 In the drawings Figure 1 is a longitudinal vertical sectional view of a steam engine embodying my invention as used in connection with a water end for pumping, the water end being broken away, and the piston in 45 the cylinder illustrated in position as it is after it has just started on its forward stroke. Fig. 2 is a similar view illustrating the piston at a point near the forward limit of its stroke. Fig. 3 is a similar view showing the piston on its backward stroke. Fig. 50 4 is a horizontal section on the line 4—4 of Fig. 3. Fig. 5 is a vertical section on the line 5—5 of Fig. 3. Fig. 6 is a horizontal sectional view through two steam engines 55 made in accordance with my invention and

connected with each other to operate as a duplex engine or as independent, simplex engines, the view being taken looking upwardly from below the cylinders. Fig. 7 is a top view looking downwardly on the tops 60 of the two cylinders arranged as a duplex engine. Fig. 8 is a vertical, sectional view on the line 8—8 of Fig. 7.

Throughout the several views similar reference numerals indicate similar parts. 65

Taking up, in the first place, a description of the simplex type of engine the numeral 1 indicates a cylinder provided with the rear head 2 and the front head 3 of the usual construction. At the rear end of the cylinder 70 1 and on the upper side thereof is the port 4 while at the front end of said cylinder and at the upper side is the port 5. More detailed description of said ports will hereinafter be given. Midway between the ends 75 of the cylinder 1 and on the upper side thereof is the auxiliary exhaust port 6 for the main, steam balanced, cylinder port controlling valve hereinafter more fully explained. Adjacent the port 6 and longitudinally spaced therefrom, one on each side, are the auxiliary ports 7 and 8, also for the main controlling valve, the said ports 6, 7 and 8 having nothing to do directly with the control of steam inlet or outlet for the 80 cylinder 1, but only being used for actuating the main balanced valve.

Within the cylinder 1 is arranged a piston provided with two longitudinally spaced heads, the rear head 9 and the front head 10 90 both connected to the piston rod 11 which extends through the front head 3 which is provided with a stuffing box 12 of any usual construction. The piston rod 11 extends forward from the head 3 and may be connected 95 to the operative mechanism of the pump end 13, or any other device which it is desired to actuate by said piston rod.

For the purpose of holding the heads 9 and 10 in proper relative position and to increase the stability of the piston structure 100 brace rods extend between said heads and are fastened thereto. The preferable arrangement of said brace rods is illustrated in the drawings, Fig. 5 most clearly showing the positions of the various rods. In said Fig. 5 it will be noted that the rods 14 and 15 are at the bottom side of the cylinder and the rods 16 and 17 at the top. The rods 16 and 17 are spaced from each other, are 110

parallel, and have oppositely disposed faces arranged substantially in planes radial with reference to the bore of the cylinder. This construction is clearly illustrated in Fig. 5.

- 5 Arranged between the rods 16 and 17 is the D valve 18 the outer side walls of which are arranged in planes radial with reference to the bore of the cylinder so as to conform to the said oppositely disposed faces of the rods 16 and 17, and which valve is held in engagement with the top wall of the cylinder by means of the said rods 16 and 17 while permitted to slide longitudinally with reference to said rods and with reference to said wall. Said valve is of such size as to extend over and inter-connect the port 6 with either one or the other of the ports 7 and 8 for the purpose which will presently be explained.

- 20 It should be noted that the valve 18 is provided at each end with a lug 19 adapted to be engaged by the heads of the piston for the purpose of slidably moving said valve, as will hereinafter appear. For the purpose 25 of conducting live steam to the engine the pipe 20 is provided, which is connected to the steam chest 21, upon which is mounted the main valve casing 22, the steam chest 21 and said casing being preferably cast integrally as illustrated in the drawings. In 30 the steam chest 21 is a longitudinally disposed cored out live steam passage 23 into which the steam is admitted from the said pipe 20. The passage 24 permanently connects the interior of the cylinder 1 between 35 the piston heads 9 and 10 with the live steam supply within the passage 23 so that at all times steam pressure is maintained between said piston heads while having no effect 40 upon said heads, as the space between said heads remains uniform at all times. The main valve casing 22 is provided with a longitudinally disposed bored valve cylinder 25 provided at each end with a stationary head 26 screwed into said cylinder, or 45 otherwise mechanically connected. At the two ends of the cored out passage 23 ports 27 and 28, to the rear and to the front of the center of the cylinder 25 are provided, 50 which ports are adapted, when uncovered, to conduct live steam from the passage 23 into said cylinder 25. In the steam chest 21 are also provided the main steam passages 29 and 30, which are longitudinally disposed, 55 the rear passage 29 being connected with the rear port 4 in the cylinder 1 and the front passage 30 being connected with the front port 5 in said cylinder. At the opposite ends of the passages 29 and 30 the ports 31 60 and 32 connect said passages with the interior of the valve cylinder 25. Extending through the body of the casing constituting the steam chest and through that portion thereof which separates the passage 23 from 65 the passages 29 and 30 are the auxiliary pas-

sages 33 and 34, the passage 33 connecting the port 8 with the rear end of the valve cylinder 25 and the passage 34 connecting the port 7 with the front end of said cylinder 25.

70 In the steam chest 21, on the opposite side from that into which the pipe 20 enters is arranged the general exhaust passage 35 from which the pipe 36 carries the exhaust steam into the atmosphere or a condenser or the like, as may be preferred. The exhaust port 6 in the cylinder 1 is connected with the exhaust passage 35 as is also the exhaust port 35^a in the valve cylinder 25.

75 Within the valve cylinder 25 is arranged a balanced piston valve which is provided with four heads indicated by the numerals 37, 38, 39 and 40 respectively, from rear to front. It will be noted from an inspection of the drawings that the said heads are 80 spaced from each other substantially equal distances and that the cylinder 25 is longer than the entire piston valve by an extent substantially equal to the distance between any two heads of the valve. When the valve 85 is in its extreme forward position, as illustrated in Fig. 1 the port 31 will be connected with the port 27 permitting live steam to pass from the passage 23 through the space between the heads 37 and 38, through the 90 port 31 into the passage 29 and thence into the rear end of the cylinder 1 behind the rear piston head 9. This will cause the piston 95 within the cylinder 1 to move forward, the exhaust steam from in front of the piston head 10 exhausting through the port 5, the passage 30, the port 32, the space between the heads 38 and 39, the exhaust port 41 and the general exhaust passage 35, and thence out through the pipe 36. When the piston has moved forward until it has attained the position illustrated in Fig. 2 the rear head 9 will come into engagement with the D valve 18, which, by the further forward movement of the piston will be slidably moved into the position illustrated in 100 Fig. 3, connecting the ports 6 and 8 and uncovering the port 7. Live steam under pressure being constantly maintained between the heads 9 and 10, said steam will enter 105 through the port 7 into the auxiliary passage 34, and thence into the valve cylinder 25 in front of the head 40 of the piston valve. The piston valve will thus be immediately moved backward into the position illustrated in Fig. 3, the steam back of the head 37 exhausting through the auxiliary passage 33 and the port 8, through the valve 18, and thence out through the exhaust passage 35 and exhaust pipe 36. As soon as 110 the piston valve has been thus moved to its rear position as illustrated in Fig. 3 steam will be admitted from the passage 23, the port 28, the space between the heads 39 and 40, the port 32, the passage 30 and the port 115 120 125 130

5 into the cylinder 1 in front of the piston head 10, thus causing the piston within the cylinder 1 to move backwardly, the steam back of the head 9 exhausting through the 5 port 4, the passage 29, the port 31, the space between the heads 38 and 39 and the exhaust port 41 into the general exhaust passage 35 and out through the pipe 36. As the piston within the cylinder 1 nears the end of its 10 rear stroke the head 10 comes into engagement with the valve 18 and slidably moves said valve backward so as to connect the ports 6 and 7 and uncover the port 8, as illustrated in Fig. 1. In this position live 15 steam will be admitted from between the heads 9 and 10 through the port 8 and the auxiliary passage 33 into the rear end of the cylinder 25 back of the head 37, thus driving the piston valve forwardly into the position 20 illustrated in Fig. 1, the steam in front of the head 40 exhausting through the auxiliary passage 34, the port 7, the valve 18 and the port 6 into the passage 35 and thence out through the exhaust pipe 36. 25 When the piston valve is thus disposed at the front end of the cylinder 25 live steam will be admitted into the cylinder 1 behind the piston head 9 which will be driven forward, as hereinbefore described, thus completing 30 a cycle of operation.

Attention should be called to the fact that it is desirable to limit the possible movement of the valve 18 by some suitable means so that it may not move beyond its 35 predetermined limits. For this purpose I employ a limiting pin 42 which extends through the wall of the cylinder 1 and has its inner end extending into the hollow of said valve 18, thus preventing the valve 40 from moving too far either forwardly or backwardly. The valve 18 is relatively small and requires but little force to move it. It is positive in operation and is so directly actuated by the piston heads as to 45 insure absolutely accurate timing after the engine has been once constructed and set up. The piston valve, as will be readily understood, is balanced and requires very little force to move it. The live steam under 50 pressure acting against the heads 37 and 40 in the ends of the cylinder 25 actuates said piston valve both positively and quickly. In fact the piston valve is almost instantaneous in its movements. By an inspection 55 of the drawings it will be noted that the cylinder wall adjacent the ports 4 and 5 is cut away slightly substantially to the heads 2 and 3 to permit the steam to enter the cylinder between the head thereof and the 60 head of the piston at either end. With these facts in mind it will be readily understood that the device operates in a positive and satisfactory manner without any undue valve friction and with the minimum 65 loss of energy within the device itself.

As hereinbefore stated two of my invented engines may be inter-connected in such way as to produce a duplex steam engine of improved design. In Figs. 6, 7 and 8 the arrangement and inter-connection of 70 two of my simplex engines to produce a duplex engine are shown. In said figures one of the two engines going to make up the duplex engine is designated A while the other is designated B. In constructing a duplex 75 engine the two simplex engines A and B each constructed in all of its parts similarly to the simplex engine hereinbefore described, are arranged side by side with their axes parallel and their piston rods extending forwardly in the same direction. The essential requirement for producing duplex action by the two engines is then merely to make such interconnections between the two engines and their parts that the D valve 80 actuated by the piston heads in each engine will control the steam supply for actuating the piston valve on the other engine. To accomplish this result I arrange in each steam chest two small valves 43^a, 44^a and 85 43^b, 44^b by which the ports 7 and 8 in each engine may be cut off from connection with their auxiliary passages 33 and 34, thus shutting off connection between each cylinder and the piston valve cylinder 90 mounted upon it. To accomplish the cross or inter-connection between the piston valve cylinder on each side and the D valve in the engine on the other side the ducts 45, 46, 47 and 48 are provided. The said ducts may 100 105 be made of pipes as shown in the drawings, or otherwise, the pipes shown in the drawings being one of the possible forms of construction. The duct 45 is connected at one end with the port 7 of the engine B and at the other end with the rear end of the piston valve cylinder on engine A. The duct 46 is connected at one end with the port 8 of engine A and at the other end with the rear end of the piston valve cylinder on engine B. The duct 47 is connected at one end with the port 7 of engine A and at the other end with the front end of the piston valve cylinder on engine B. The duct 48 is connected at one end with the port 8 of engine B and at the other end with the front end of the piston valve cylinder on engine A. On each of the ducts 45, 46, 47 and 48 a valve 49 is provided whereby the passage 110 through said duct may be closed. The two engines and their inter-connections being arranged as just described and the valves 43^a, 44^a, 43^b, 44^b closed and the valves 49 open the D valve 18 in each engine will control the supply of steam for actuating the piston valve on the other engine as will be readily understood by those skilled in the art, whereupon duplex operation of the two simplex engines will be produced. Should 115 it be desired at any time to operate only one 120 125 130

of the engines or to operate the two engines as a pair of simplex engines the valves 49 may be closed and the valves 43^a, 44^a, 43^b, 44^b open, whereupon steam inter-connection between the two engines will be cut off and appropriate connections established in each engine to cause it to operate as a simplex engine, as will be readily understood by those skilled in the art in view of the description hereinbefore given as to the structure and operation of the simplex engine illustrated in Figs. 1 to 5 inclusive.

I claim:—

In a device of the character described two engines arranged side by side, each engine having a cylinder, a spaced-headed piston in said cylinder, said cylinder provided with ports for conducting piston-actuating steam into and from said cylinder, said cylinder also provided with auxiliary ports intermediate the heads of said piston, a steam-actuated piston-valve on the outside of said cylinder, said piston-valve connected with the said ports in said cylinder by main steam-conducting passages, said piston-valve adapted to control the piston-actuating steam supply to and from said cylinder through said main passages, means for conducting steam

under pressure into said cylinder between the spaced heads of the piston, an auxiliary valve located wholly within said cylinder between the spaced heads of said piston and adapted to be bodily moved by the spaced heads of said piston to open and close said auxiliary ports in said cylinder to control the steam supply from between said spaced heads through said auxiliary ports, said auxiliary ports and said piston-valve connected by auxiliary steam-conducting passages, means for connecting the steam-actuated piston-valve of each engine with the auxiliary ports in the cylinder of the other engine by supplemental, auxiliary steam-conducting passages, means for opening and closing said auxiliary steam-conducting passages, and means for opening and closing said supplemental, auxiliary steam conducting passages.

In testimony that I claim the above, I have hereunto subscribed my name in the presence of two witnesses.

ELIAS W. CONKELL.
